TELEGRAPHIC TAPE TRANSMITTER

Waldo G. Rice, Chicago, Ill.

Application January 6, 1940, Serial No. 312,626

16 Claims. (Cl. 178—17)

This invention relates to telegraphic tape transmitters and more particularly to automatic tape transmitters for use in connection with the start-stop type of telegraph printers, although such may be employed with equal advantage for other purposes.

It contemplates more especially the provisions of an exceedingly simple, inexpensive, compact, and dependable automatic tape transmitter requiring minimum energy drain so that their multiple connection to telegraphic or similar electrical systems will not impair signal transmission or reception.

Telegraph printers employing the start-stop principle of operation are now widely used with limited exceptions; however, manual keyboard transmission is still the common practice. It is well known that stored up work in the form of perforated tape displaced through a transmitter advances greatly wire and labor economy and speed of operation. Some of the larger telegraph offices are now equipped with an independent tape transmitting unit with necessary floor space comprising a table upon which a motor, distributor and speed regulator in addition to the transmitter is mounted with extensive plugging in arrangements. The cost of this equipment is relatively high so that one tape transmitter is designed to operate on many wires. This method of plugging in by turns and waiting for assignments in the use of one unit entails delays, attendant's time in making switches, and other disadvantages not conducive to volume or efficient operation.

With the teachings of the present invention, every keyboard distributor in any office having a tape perforator and/or receiving tape by reperforators from distant offices for relay, is provided with a tape transmitter fixed thereto by fastening to the side of the keyboard and having plug cable connection to the keyboard for instantaneous operative connection therewith. Simplicity and inexpensive construction together with dependability of operation, is effected with improved contacts that frictionally glide over the perforated tape without any loss of pulse.

This coupled with a simplified feed pawl serving as a direct link between a very light armature and feed roll, insures instantaneous movement of the tape with the expenditure of negligible power. This is accomplished by the use of a solenoid and relay of very low wattage requirement and yet procures the desired power of response with a current value that is a mere fraction of that required by transmitters of known construction for

transmission of signals without distortion for multiple redistribution. These features overcome the complicated lever actions, high wattage requirements, and the time element involved with the comparatively heavy solenoids used in transmitters of known construction.

One object of the present invention is to provide a transmitter that will feed tape instantaneously by connecting the stop pulse at the customary current value which at present is approximately 50 milliamperes from the main line direct through the feed magnet or through a relay operating the feed magnet.

Another object is to provide a simple, light, compact and sturdy tape transmitter of inexpensive construction possessed of negligible maintenance requirements to serve as a substitute for manual message transmission with any type of keyboard distributor.

An additional object is to simplify the construction and improve the operation of devices of the character mentioned.

Still another object of the present invention is to provide an automatic tape transmitter of inexpensive construction and dependable operation in conjunction with a keyboard telegraph distributor for effecting automatic transmission and redistribution.

A further object is to provide an improved device for automatic message transmission responsive to the traverse of perforated paper tape to effect message transmission and/or redistribution responsive to a feeding solenoid of low energy drain.

Still a further object is to provide improved message tape contact feelers that effect more dependable signal transmission responsive to a code perforated tape or other medium of message transmission.

Still a further object is to provide an improved electromagnetic tape feeding mechanism possessed of an unusually high power factor resulting in a low energy drain.

An additional object is to provide an improved compact, highly efficient and dependable telegraphic tape transmitter of inexpensive construction.

Other objects and advantages will appear from the following description of an illustrative embodiment of the present invention.

Figure 9 is a perspective view of a pawl feed plate shown in position in Figure 2.

Figure 10 is a diagrammatic wiring diagram of a Mux circuit embodying the transmitter solenoids, relays, distributor contacts, transmitter mechanism, and auto stop lever comprising conventional parts of a telegraph system, except for the transmitter structure which embodies features of the present invention.

Figure 11 is a plan view of a modified embodiment of the present invention, parts thereof being broken away to clarify the showing.

Figure 12 is a sectional view in elevation taken substantially along line XII—XII of Figure 11.

Figure 13 is a fragmentary view in elevation of the top portion of the transmitter shown in Figure 11.

Figure 14 is a bottom view of the top frame plate assembly shown in Figure 13.

Figure 15 is a sectional view taken substantially along line XV—XV of Figure 11.

Figure 16 is a sectional perspective view of the top frame adjustable code feeler contacts embodying features of the present invention.

Figure 17 is an enlarged plan view of the code feeler contacts and supporting plate shown in assembled position in Figure 16.

The structure selected for illustration comprises a suitable transmitter tape sustaining plate 10 that has a depressed trough 11 sized to receive a tape 12 therein for guided traverse along a predetermined path across the plate 10. The depressed trough 11 extends along the top transmitter plate 10 and is substantially of rectangular configuration to define upstanding spaced walls serving as a gate to guide the code perforated tape 12 thereover. The tape 12 has feed holes 13 along the longitudinal length thereof and message impulse code perforations 14 that are provided therein in predetermined rows determined by the letter code to correspond with the keyboard arrangement of a telegraphic transmitter. Another plate 15 confronts the tape sustaining plate 10 and is connected thereto by means of corner bolts 16 which are joined thereto by spaced fastener nuts 17 threaded thereto on both sides of the plates 10—15 to define a rigid frame with the lower plate 15 serving as a base therefor.

The tape feeding mechanism comprises, in this instance, a shaft 18 which is disposed transversely of the tape guiding groove 11 for journaled rotation in bearing brackets 19 supported by the underside of the frame plate 10. As shown, a ratchet wheel 20 is fixed near one extremity of the shaft 18 for cooperation with a pawl 21. The pawl 21 comprises, in this instance, a threaded stud projecting through a correspondingly threaded aperture 22 in the extremity of an inverted T-shaped plate 23 to control the intermittent rotation of the shaft 18 in conjunction with a feed wheel 24. The feed wheel 24 has a plurality of radially projecting studs 25 provided on the periphery thereof for meshing en-

gagement with the linear line of feed perforations 13 provided in the tape 12 for positive feeding along a predetermined linear path.

In order to maintain the tape 11 in registry with the studs or spokes 25 provided on the feed wheel 24, a flat substantially rectangular tape retaining lid 26 is pivoted to a bracket plate 27 attached to the transmitter frame plate 10 to effect pivotal connection therebetween through the medium of hinges 28. In order to maintain the lid 26 in operative connection with the transmitter frame plate 10, a roller latch mechanism 29 cooperates with a spring clip 30 anchored to the frame plate 10 at its base 31, by fasteners 32. This affords the retention of the tape retaining plate 26 in position and provides for the instantaneous connection and disconnection of the cooperating parts. A protective plate member 33 having a finger manipulating extension 34 is fastened to an upstanding bracket 35 anchored as at 36 to the tape retaining lid 26. This enables the lowering and lifting of the tape retaining plate 26 into and out of engagement with the spring latch 29—30 to manipulate and control the position thereof.

Now, then, the lid 26 has a rectangular depending projection 37 which substantially conforms in shape and configuration with the tape receiving groove guide 11 provided in the tape guide plate 10. The groove guide 11 is somewhat larger so as to telescopically receive the lid projection 37 with the tape 12 therebetween so as to hold the latter in a taut position when the retaining lid latch 29—30 engages the transmitter frame 12 (Figure 4). The complementary association of the lid 26 with its projection 37 in the guide 11 of the plate 10 with the tape 12 therebetween is effected without appreciable friction thereon so that the tape 11 is free for linear traverse responsive to the intermittent rotation of the feed wheel 24 that has its studs 25 in meshing engagement with the tape feed perforations 13.

In order to accommodate the studs or spokes 25 that project through the linear line of feed holes or perforations 13 in the tape 12, the lid 26 is provided with a notch 38 that extends inwardly from one edge of the region within the depending projection 37 so that the studs 25 can project through the feed holes 13 and freely extend into the lid 26 without obstruction thereto to insure proper meshing engagement with the feed perforations of the tape 11. To transmit the messages quoted by predetermined perforations 14 in the tape 12, a plurality of wire contact feelers 39, in this instance five, are soldered or otherwise secured along the open end portion 40 thereof to an inclined metallic plate 41 which is provided with spaced and horizontally disposed supporting and attaching plates 42—43 to sustain the inclined member 41 in position with the wire feelers 39 projecting downwardly therefrom along the surface of the plate 41.

Suitable fasteners such as threaded studs 44 project through the supporting plates 42—43 to effect their detachable connection to the tape retaining shoe or lid 26. A threaded stud 45 is anchored to the inclined plate 41 for enabling the connection of a wire lead thereto. It will be observed that the inclined top portion 41 supporting wire contact feelers 39 is disposed beneath the finger manipulating and projective plate member 34 described supra so as to conceal such from accidental impact or finger grasp.

It is to be noted that each of the five wire feelers 39 are bunched to include a plurality of

closely associated individual wires of substantially the same length, in this instance numbering five or six, so that the downwardly extending extremities 46 thereof will establish resilient contact with the message tape 12 when the shoe or lid 26 is in its operative position effecting interengagement of the complementary latch members 29-30. The wire feelers 39 are spaced along the inclined plate 41 to correspond with the spacing of the end perforations 14 so that each will be disposed in alignment therewith to project therethrough as the message tape 12 is displaced along the guide groove 11.

It is to be noted that a plurality of terminal pins 47, in this instance five, are transversely anchored across the guide groove 11 for communication therewith to correspond with the spacing of the perforations 14 in the tape 12, and these are axially aligned with each of the wire feelers 39 so as to confront each other in resilient frictional contact when the message tape 12 has been removed from the groove 11 or perforations 14 are aligned with the code pins 47 so that the free extremities 46 of the wire feelers 39 will project therethrough as the tape 12 is displaced along its predetermined path as will appear more fully hereinafter. It will be observed that the wire feelers 39 will always be in registry with the upper extremities of the code pins 47 while the shoe or lid 26 has its depending projection 37 releasably held in operative position to smoothly retain the tape 12 in the groove 11 during its traverse along the predetermined path provided in the plate 10. The tape 12 is held in alignment in that the groove 11 in the plate 27 is always in registry with the shoe projection 37 of the lid 26, the latter being loosely held in position by the latch members 29-30.

The code pins or terminals 47, in this instance five, are tightly pressed in to extend through transversely arranged holes of slightly smaller diameter than the pins 47. It will be apparent, therefore, that the code terminals 47 will be displaced in the path of the code perforation 14 provided in the tape 12 so that signal transmission will be effected as the code feelers establish contact therewith through the top apertures 14. In order to impart intermittent movement to the tape 12 responsive to corresponding rotation of the feed wheel 24, the pawl 23 cooperates with the ratchet wheel 20. The ratchet wheel 20 is displaced by the reciprocal movement of the pawl 23 and held in successive stepped position by means of a roller 48 mounted on a pin 50, the latter being carried by a lever 51 which is pivoted as at 52 to a depending bracket plate 53.

The bracket plate 53 is secured to the underside of the upper supporting frame plate 10 to serve as a mount for a substantially U-shaped spring 54 that has one extremity anchored as at 55 in the lever 51 to normally urge the latter to assume an extreme counterclockwise position (viewed from Figure 2) so that the roller 48 will be in engagement with the peripheral teeth on the ratchet wheel 20 to insure intermittent stepped rotation thereof. In order to hold the substantially U-shaped spring 54 against lateral displacement, a transverse flange 56 is attached to the face of the bracket plate 53 so that the spring 54 will be held in a vertical plane adjacent thereto.

As shown, the pawl 23 depends downwardly in the substantially T-shaped head that is provided with an elongated slot 57 to receive therethrough the extremity 58 of the solenoid armature 59 that

is pivoted to an armature 60 (Figure 2) constituting an upstanding portion of a coarse supporting plate 61. The solenoid 62 is mounted axially by means of a fastener 63 to the armature supporting plate 61 of the lower frame plate 15. The solenoid pawl 23 is held in operative position on the solenoid arm 59 by means of a spring 64 that is anchored to the head of a threaded stud 65 engaging a correspondingly threaded aperture 66 provided in the arm of the pawl 23 (Figure 9).

The other extremity of the spring 64 is anchored in a stud 67 carried by the solenoid armature 59 which is held in its extreme inoperative clockwise position (viewed from Figure 2) by means of a spring 68. The spring 68 is anchored to a stud 69 carried by the extremity of the solenoid armature 59 while the other end thereof is anchored to a stud 70 anchored proximate to the lower end of the upstanding bracket arm 60. It will be apparent, therefore, that with the reception of the feed bolts, the solenoid 62 will be directly or indirectly energized to draw its armature 59 downwardly in a clockwise direction to impart intermittent rotation to the feed wheel 20 that correspondingly moves the tape 12 along the groove or depressed trough 11 provided in the upper frame plate 10.

Simultaneously with the movement of the tape 12, the code feeler 39 is connected to one end of the distributor line to effect contact with the code pins 47 wherever impulse code perforations 14 appear in the tape 12 as will appear more fully from the schematic wiring diagram illustrated in Figure 10. So that there will be no signal transmission nor operation of the feed wheel 24 in the event any break occurs in the tape 12 or the latter has been entirely displaced over the code terminals 47, automatically operable tape stop instrumentalities 71 and 72 are mounted in the depressed trough 11 (Figure 3) in the manner fully illustrated and described in Letters Patent of the United States Number 2,074,189 and issued March 16, 1937.

In order to preclude the necessity of incorporating the tape feed solenoid 62 directly in the transmission line and thus reduce the strength of the signals transmitted thereover, the latter is rendered responsive to a relay 73 mounted as at 74 on the lower frame plate 15 to cooperate with its armature 75 that is rendered adjustable by a threaded stud 76. The relay coil 73 is connected to the sixth pulse for operation responsive to each signal received thereover and it, in turn, controls the operation of the solenoid 62 which moves the tape 12 forward. It should be appreciated that because the relay coil 73 possesses trivial resistance value and is far more sensitive for signal response than the solenoid 62 which has the necessary power to operate the tape feeding mechanism, the transmitter 10 can be incorporated in the pulse circuits of a telegraph system without impairing the operating margin of the current intensity required for the primary distributor and printer.

A transmitter lever cut-out switch 77 is, in this instance, pivotally mounted as at 78 to the lower frame plate 15 for cooperation with terminal contacts 79 or 80 provided therein. As a result, the cut-out lever switch 77 can be utilized to control the operation of the transmitter. As shown, the code terminals 47 are connected through the proper lead wires confined in a flexible conduit 81 that terminates in a plug 82 that is instantly attachable and detachable to a com-

plemental plug (not shown) for placing the transmitter 10 in operation without the necessity of special wiring of any kind and rendering such immediately useful in any line for direct connection to the distributor.

In the modified embodiment shown in Figures 11 to 17 inclusive, a top frame plate 10' is provided with a recess depressed trough 11' for cooperation with a lid or shoe 26' hinged as at 28' for retention in operative position by the latch members 29'-30'. A protective plate member 33' together with an extension 34' is supported by a threaded stud 35' by means of spaced correspondingly threaded nuts 36' which engage the stud 35' on both sides of the protective plates 33'. The plate extension 34' enables the manipulation of the lid or shoe 26' for displacement relative to its hinge 28' to assume an operative or inoperative position. It will be observed that the protective plate 34' is disposed over and serves as a shield for a plurality of code contact feelers 39', in this instance five, soldered or otherwise secured along the free extremity 40' of a plate 41'.

The plate 41' has a substantially U-shaped notch 42' provided centrally along the longitudinal median line thereof for the reception of a threaded stud 43'. The threaded stud 43' projects through a cap plate 44' that confronts the wire feeler contact mounting plate 41' to engage a correspondingly threaded aperture provided in a transverse bar 45' on the underside wire feeler mounting plate 41'. As shown, the bar 45' has an axially threaded stub shaft 46' (Figure 15) that is journaled in a bore 47' provided in an upstanding bracket 48' having its flange 49' attached to the top surface of the lid or shoe 26'.

A dished plate 50' is disposed over the stub shaft 46' of the bar 45', and a pair of nuts 51' and 52' threadedly engage the axial bar stub shaft 46' to support the wire feeler mounting bar 45' in any adjustable rotary position, the bar 45' being frictionally held in its rotary adjustable position through the urge of the dished resilient plate 50' that is frictionally held by the nut 51' and its lock nut 52'. In order to manipulate the wire feeler contact mounting bar 45' in its angular adjusted position, a lever 53' provided with a polygonal bore in the extremity 54' thereof, serves as a complement of the corresponding polygonal shape provided on the base 55' (Figure 15) of the stub shaft 46' so that rotary movement imparted to the lever 53' will effect corresponding rotation of the bar 45' serving as a mount for the feeler contact plate 41'.

The lever 53' is preferably of thin resilient sheet material that cooperates with a vertical strip 56' adhesively or otherwise attached to the upstanding bracket 48' in the path of the lever 53' so as to have frictional surface engagement therewith to hold the feeler contact mounting bar 45' in any adjusted angular position. A lug 57' of somewhat thicker material than the vertical strip 56' is preferably though not essentially attached to the upstanding bracket 48' in a superposed position with respect to the strip 56' so as to preclude the accidental clockwise displacement of the lever 53' beyond the upward limit which defines the operative position of the code feeler contacts 39'.

To enable the lever 53' to pass to the lug 57' when in position thereabove, it is necessary to effect the inward flexing thereof so that the lever 53' will be momentarily free from the obstruc-

tion offered by the lug 57'. The free extremity 58' of the lever 53' is preferably though not essentially somewhat offset inwardly to enable the convenient finger grasp thereof in positioning the wire contact feelers 39'. With this arrangement, it will be observed that each wire feeler 39' is composed of a plurality of individually closely associated wires, in this instance six, that are disposed in inclined position aligned with the surface of their mounting plate 41' to project downwardly therefrom with their free extremities engaging correspondingly spaced code pin terminals 59' that extend upwardly through the top frame plate 10'.

It will be observed, therefore, that the wire feeler contacts 39' can be displaced to any adjusted position for answering the desired frictional engagement with the upper extremities of the code pin terminals 59' or such may be removed entirely from contact therewith by displacing the lever 53' in a clockwise direction (viewed from Figure 16) to permit tape threading. Further, the journaled support of the bar 45' together with the lever 53' enables any adjustment to be effected between the wire feeler contacts 39' and the code pin terminals 59'. The remaining parts are precisely the same as those shown in the preceding embodiment.

A distributor 85 (see schematic wiring diagram—Figure 10) is started manually by a latch (not shown). Pulses 1-2-3-4-5 are code pulses. Pulse 6 is a feed and stop pulse and together with conductor 1 constitutes the energy source for operating the relay coil 73. The eighth conductor (8) serves as a shunt for pulse contacts 1-2-3-4-5-6 effective whenever there is no tape 12 passing over the automatic tape stop pin 71 or there is a tear in the tape 12. The distributor 85 causes contacts to close and open successively 1-2-3-4-5-6—1-2-3-4-5-6 or any combination thereof, only one contact being closed at any one time to transmit the selected message. The eight conductors are connected by appropriate leads terminating in the cord 81 to the terminal jacks in the plug 82 so that the transmitter 10 can be readily connected and disconnected to the distributor 85. The term "solenoid" is generically used throughout the description as the equivalent of the term "electromagnet," and no distinction is to be asserted therebetween in interpreting this disclosure. The operation of the instrumentalities is apparent from an examination of the schematic wiring diagram (Figure 10) and this will be described in detail in my co-pending application Serial Number 313,807, and filed Jan. 15, 1940 patented Feb. 17, 1942 No. 2,273,378, directed to the operating circuit which is more completely illustrated and described therein.

Various changes may be made in the embodiment of the invention herein specifically described without departing from or sacrificing any of the advantages or features thereof, and nothing herein shall be construed as limitations upon the invention, its concept or structural embodiment as to the whole or any part thereof except as defined in the appended claims.

I claim:

1. In a telegraph transmitter, the combination with means for guiding the traverse of code perforated transmission tape along a predetermined path, of a plurality of pulse circuits including confronting normally engageable contacts disposed in said path for normal separation by said transmission tape unless signal code perforations

or interruptions appear therein, and tape feeding means for directing said perforated transmission tape past said confronting contacts to control the closing of one or more of said pulse circuits to effect message transmission.

2. In a telegraph transmitter, the combination with means for guiding the traverse of code perforated transmission tape along a predetermined path, of a plurality of pulse circuits including confronting contacts disposed in said path, said confronting contacts including resilient tape perforation feelers in normal frictional engagements with non-yielding terminals for normal separation by said transmission tape unless signal code perforations or interruptions appear therein, and tape feeding means for directing said transmission tape past said confronting contacts to control the closing of one or more of said pulse circuits to effect message transmission.

3. In a telegraph transmitter, the combination with means for guiding the traverse of code perforated transmission tape along a predetermined path, of a plurality of pulse circuits including confronting contacts disposed in said path, said confronting contacts including resilient tape perforation feelers, each of said resilient tape perforation feelers comprising a plurality of fine wires having free extremities in normal frictional engagements with non-yielding terminals for normal separation by said transmission tape unless signal code perforations or interruptions appear therein, and electrically operated tape feeding means for directing said transmission tape past said confronting contacts to control the closing of one or more of said pulse circuits to effect message transmission.

4. In a telegraph transmitter, the combination with means for guiding the traverse of code perforated transmission tape along a predetermined path, of a plurality of pulse circuits including confronting contacts disposed in said path, said confronting contacts including resilient tape perforation feelers, each of said resilient tape perforation feelers comprising a plurality of fine wires, a common electrical conductor mount for said resilient tape perforation feelers with their extremities in normal frictional engagements with nonyielding terminals for normal separation by said transmission tape unless signal code perforations or interruptions appear therein, and electrically operated tape feeding means for directing said transmission tape past said confronting contacts to control the closing of one or more of said pulse circuits to effect message transmission.

5. In a telegraph transmitter, the combination with means for guiding the traverse of code perforated transmission tape along a predetermined path, of a plurality of pulse circuits including confronting contacts disposed in said path, said confronting contacts including resilient tape perforation feelers, each of said resilient tape perforation feelers comprising a plurality of fine wires, a common electrical conductor mount for said resilient tape perforation feelers with their extremities in normal frictional engagements with non-yielding terminals for normal separation by said transmission tape unless signal code perforations or interruptions appear therein, adjusting means for varying the degree of engagement between said confronting contacts, and tape feeding means for directing said transmission tape past said confronting contacts to control the closing of one or more of said pulse circuits to effect message transmission.

6. In a telegraph transmitter, the combination with means for guiding the traverse of code perforated transmission tape along a predetermined path, of a plurality of pulse circuits including confronting contacts disposed in said path, said confronting contacts including resilient tape perforation feelers, each of said resilient tape perforation feelers comprising a plurality of fine wires, a common electrical conductor mount for said resilient tape perforation feelers with their extremities in normal frictional engagements with non-yielding terminals for normal separation by said transmission tape unless signal code perforations or interruptions appear therein,
- 5 means for adjusting said conductor mount to vary the degree of feeler contact with their confronting terminals, and tape feeding means for directing said transmission tape past said confronting contacts to control the closing of one or
- 10 more of said pulse circuits to effect message transmission.
- 15
- 20

7. In a telegraph transmitter, the combination with means for guiding the traverse of code perforated transmission tape along a predetermined path, of a plurality of pulse circuits including confronting contacts disposed in said path, said confronting contacts including resilient tape perforation feelers, each of said resilient tape perforation feelers comprising a plurality of fine wires, a common electrical conductor mount for said resilient tape perforation feelers with their extremities in normal frictional engagements with non-yielding terminals for normal separation by said transmission tape unless signal code perforations or interruptions appear therein, means for pivotally adjusting said conductor mount to vary the degree of feeler contact with their confronting terminals, and tape feeding means for directing said transmission tape past said confronting contacts to control the closing of one or more of said pulse circuits to effect message transmission.

8. In a telegraph transmitter, the combination with means for guiding the traverse of code perforated transmission tape along a predetermined path, of a plurality of pulse circuits including confronting contacts disposed in said path, said confronting contacts including resilient tape perforation feelers, each of said resilient tape perforation feelers comprising a plurality of fine wires, a common electrical conductor mount for said resilient tape perforation feelers with their extremities in normal frictional engagements with non-yielding terminals for normal separation by said transmission tape unless signal code perforations or interruptions appear therein, means for pivotally adjusting said conductor mount to vary the degree of feeler contact with their confronting terminals, frictional holding means for said pivotally adjusting contact means, and tape feeding means for directing said transmission tape past said confronting contacts to control the closing of one or more of said pulse circuits to effect message transmission.

65 9. In a telegraph transmitter, the combination with means for guiding the traverse of code perforated transmission tape along a predetermined path, of a plurality of pulse circuits including confronting normally engageable contacts disposed in said path for normal separation by said transmission tape unless signal code perforations or interruptions appear therein, and electrical magnetic tape feeding means for directing said transmission tape past said contacts.

70

75

fronting contacts to control the closing of one or more of said pulse circuits to effect message transmission.

10. In a telegraph transmitter, the combination with means for guiding the traverse of code perforated transmission tape along a predetermined path, of a plurality of pulse circuits including confronting normally engageable contacts disposed in said path for normal separation by said transmission tape unless signal code perforations or interruptions appear therein, and electrical relay pulse controlled magnetic tape feeding means for directing said transmission tape past said confronting contacts to control the closing of one or more of said pulse circuits to effect message transmission.

11. In a telegraph transmitter, the combination with means for guiding the traverse of code perforated transmission tape along a predetermined path, of a plurality of pulse circuits including confronting normally engageable contacts disposed in said path, said confronting contacts including resilient tape perforation feelers in normal frictional engagements with non-yielding terminals for normal separation by said transmission tape unless signal code perforations or interruptions appear therein, and electrical magnetic tape feeding means including a ratchet mechanism for directing said transmission tape past said confronting contacts to control the closing of one or more of said pulse circuits to effect message transmission.

12. In a telegraph transmitter, the combination with means for guiding the traverse of code perforated transmission tape along a predetermined path, of a plurality of pulse circuits including confronting contacts disposed in said path, said confronting contacts including resilient tape perforation feelers, each of said resilient tape perforation feelers comprising a plurality of fine wires having free extremities in normal frictional engagements with non-yielding terminals for normal separation by said transmission tape unless signal code perforations or interruptions appear therein, and electrical relay pulse controlled magnetic tape feeding means for directing said transmission tape past said confronting contacts to control the closing of one or more of said pulse circuits to effect message transmission.

13. In a telegraph transmitter, the combination with means for guiding the traverse of code perforated transmission tape along a predetermined path, of a plurality of pulse circuits including confronting contacts disposed in said path, said confronting contacts including resilient tape perforation feelers, each of said resilient tape perforation feelers comprising a plurality of fine wires, a common electrical conductor mount for said resilient tape perforation feelers with their extremities in normal frictional engagements with non-yielding terminals for normal separation by said transmission tape unless signal code perforations or interruptions appear therein, adjusting means for varying the degree of engagement between said confronting contacts, and electrical magnetic tape feeding means including a pawl and ratchet mechanism for intermittently directing said transmission tape past said confronting contacts to control

the closing of one or more of said pulse circuits to effect message transmission.

14. In a telegraph transmitter, the combination with means for guiding the traverse of code perforated transmission tape along a predetermined path, of a plurality of pulse circuits including confronting contacts disposed in said path, said confronting contacts including resilient tape perforation feelers, each of said resilient tape perforation feelers comprising a plurality of fine wires, a common electrical conductor mount for said resilient tape perforation feelers with their extremities in normal frictional engagements with non-yielding terminals for normal separation by said transmission tape unless signal code perforations or interruptions appear therein, means for adjusting said conductor mount to vary the degree of feeler contact with their confronting terminals, and electrical relay pulse controlled magnetic tape feeding means for intermittently directing said transmission tape past said confronting surfaces to control the closing of one or more of said pulse circuits to effect message transmission.

15. In a telegraph transmitter, the combination with means for guiding the traverse of code perforated transmission tape along a predetermined path, a plurality of pulse circuits including confronting contacts disposed in said path, said confronting contacts including resilient tape perforation feelers, each of said resilient tape perforation feelers comprising a plurality of fine wires, a common electrical conductor mount for said resilient tape perforation feelers with their extremities in normal frictional engagements with non-yielding terminals for normal separation by said transmission tape unless signal code perforations or interruptions appear therein, means for pivotally adjusting said conductor mount to vary the degree of feeler contact with their confronting terminals, and electrical magnetic tape feeding means for intermittently directing said transmission tape past said confronting contacts to control the closing of one or more of said pulse circuits to effect message transmission.

16. In a telegraph transmitter, the combination with means for guiding the traverse of code perforated transmission tape along a predetermined path, of a plurality of pulse circuits including confronting contacts disposed in said path, said confronting contacts including resilient tape perforation feelers, each of said resilient tape perforation feelers comprising a plurality of fine wires, a common electrical conductor mount for said resilient tape perforation feelers with their extremities in normal frictional engagements with non-yielding terminals for normal separation by said transmission tape unless signal code perforations or interruptions appear therein, means for pivotally adjusting said conductor mount to vary the degree of feeler contact with their confronting terminals, frictional holding means for said pivotally adjusting contact means, and electrical relay pulse controlled magnetic tape feeding means for intermittently directing said transmission tape past said confronting contacts to control the closing of one or more of said pulse circuits to effect message transmission.
